CLAIM

The ornamental design for a shoe, as shown and described.

DESCRIPTION

The patent or application file contains at least one drawing executed in color. Copies of this patent or patent application publication with color drawing(s) will be provided by the Office upon request and payment of the necessary fee.

FIG. 1 is a side view of a shoe showing my new design.

FIG. 2 is another side view thereof.

FIG. 3 is a front view thereof.

FIG. 4 is a back view thereof.

FIG. 5 is a top view thereof.

FIG. 6 is a bottom view thereof; and,

FIG. 7 is a front perspective view thereof.

The even dashed broken lines represent the boundary of the claim and form no part of the claimed design. The translucent shaded portions of the footwear shown inside the perimeter of the even dashed broken lines form no part of the claimed design.
